US0D1096635S

(12) **United States Design Patent** (10) **Patent No.:** **US D1,096,635 S**
Elison et al. (45) **Date of Patent:** **** Oct. 7, 2025**

(54) **INTERFACE FOR VEHICLE BATTERY**

(71) Applicants: **CPS Technology Holdings LLC**, New York, NY (US); **Clarios Advanced Solutions GmbH**, Hannover (DE)

(72) Inventors: **Nicholas E. Elison**, Mequon, WI (US); **Jeffrey Michael Watts**, Milwaukee, WI (US); **Christopher M. Bonin**, South Milwaukee, WI (US); **Marco Jansen**, Lower Saxony (DE); **Joerg Birkholz**, Lower Saxony (DE); **Ethan Michael Corr**, Milwaukee, WI (US)

(73) Assignees: **CPS Technology Holdings LLC**, New York, NY (US); **Clarios Germany GmbH & Co. KG**, Hannover (DE)

(**) Term: **15 Years**

(21) Appl. No.: **29/872,207**

(22) Filed: **Mar. 8, 2023**

(51) LOC (15) Cl. **13-02**

(52) U.S. Cl.

USPC **D13/120**; D13/103

CLAIM

The ornamental design for an interface for vehicle battery, as shown and described.

DESCRIPTION

FIG. 1 is a front perspective view of an interface for vehicle battery;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines shown in the drawings are for the purpose of illustrating portions of the interface for vehicle battery and form no part of the claimed design.

1 Claim, 7 Drawing Sheets
